BY Robert J. Mihle, Jr.

ATTORNEY

UNITED STATES PATENT OFFICE

GEORGE B. McCORMACK, OF CHICAGO, ILLINOIS

PRINTING-INK KNIFE OR THE LIKE

Application filed January 4, 1929. Serial No. 330,401.

My invention relates particularly to printing ink knives such as are used about printing presses for transferring ink to and from the ink fountains of the presses and for stirring the ink in the fountains to maintain the ink in a uniformly mixed condition, although not limited to these uses alone.

The main object of the invention resides in the provision of a knife of the above type which is particularly effective in mixing the ink in the ink fountains of printing presses, at the same time being adapted for all of the uses to which such knives are put.

With this object in view my invention consists in certain features of novelty in the construction, combination and arrangement of parts by which the said object and certain other objects, hereinafter appearing, are effected, all as fully described with reference 20 to the accompanying drawing and more particularly pointed out in the appended claims.

In the said drawing—

Figure 1 is a side elevation of a knife embodying my invention, and

25 Figure 2 is an edge elevation of the same.

Like characters of reference indicate like parts in the several views.

Referring to the drawing, 1 designates a usual handle, and fixed on the handle and 30 extending therefrom in adjacently spaced edgewise relation are two blades 2 and 3, the blades being fixed in the handle by means of shanks 4 thereof being engaged in a slot in the handle and secured therein by rivets 5 passing through registering holes in the handle and shanks.

The outer longitudinal edge 6 of the blade 2 is straight and this blade has a straight transverse outer end edge 7 for use in scraping out ink containers, ink fountains and the like.

40 The inner longitudinal edge of the blade 2 is sinuous, as designated at 8, and the longitudinal edges of the blade 3 are sinuous, as designated at 9, the inner longitudinal edge of the blade 3 preferably corresponding with the inner longitudinal edge 8 of the blade 2.

Ink is mixed in the ink fountains of printing presses by passing the blades of the knife substantially facewise through the ink, it be-

ing observed that the blades provide four edges for the ink to pass over, thus affording a quick mixing of the ink, the three sinuous edges 8 and 9 of the blades further aiding in the mixing.

55 The blade 3 is preferably narrower and consequently more flexible than the blade 2 so that under the pressure of the ink in the mixing thereof the blade 3 is flexed out of its normal relation with the blade 2 thus widening 60 the space between the blades for the passage of ink therebetween.

While I have herein shown and particularly described the preferred embodiment of my invention I do not wish to be limited to the 65 precise details of construction shown as changes may readily be made without departing from the spirit of my invention, but having thus described my invention, I claim as new and desire to secure by Letters Patent the 70 following:—

1. In a printing ink knife or the like the combination of two blades mounted on a handle and extending therefrom in adjacently spaced edgewise relation, one of said blades 75 having its outer longitudinal edge straight and having its inner longitudinal edge sinuous, and the other blade having both of its longitudinal edges sinuous.

2. In a printing ink knife or the like the combination of two blades mounted on a handle and extending therefrom in adjacently spaced edgewise relation, one of said blades having its outer longitudinal edge straight and having a straight transverse outer end 80 edge and having its inner longitudinal edge sinuous, and the other blade having both of its longitudinal edges sinuous.

3. In a printing ink knife or the like the combination of two blades mounted on a handle and extending therefrom in adjacently spaced edgewise relation, one of said blades having its outer longitudinal edge straight and having its inner longitudinal edge sinuous, and the other blade having both of its 95 longitudinal edges sinuous, one of said blades being more flexible than the other.

4. In a printing ink knife or the like the combination of two blades mounted on a handle and extending therefrom in adjacently 100

spaced edgewise relation, one of said blades having its outer longitudinal edge straight and having a straight transverse outer end edge and having its inner longitudinal edge sinuous, and the other blade having both of its longitudinal edges sinuous with the inner longitudinal edge thereof corresponding with the inner longitudinal edge of the other blade and being more flexible than the other blade.

10 In witness whereof I hereunto affix my signature this 3rd day of December, 1928.

GEORGE B. McCORMACK.
